UNITED STATES PATENT OFFICE.

RUDOLPH REJSEK, OF NEW YORK, N. Y., ASSIGNOR TO AMERICAN MACHINE & FOUNDRY COMPANY, OF NEW YORK, N. Y., A CORPORATION OF NEW JERSEY.

SPOUT FOR INSERTING PACKAGES IN RECEPTACLES.

1,132,032.

Specification of Letters Patent. Patented Mar. 16, 1915.

Application filed December 26, 1914. Serial No. 379,113.

To all whom it may concern:

Be it known that I, RUDOLPH REJSEK, a subject of the Emperor of Austria-Hungary, residing at New York, county of New York, and State of New York, have invented a new and useful Improvement in Spouts for Inserting Packages in Receptacles, of which the following is a specification.

10 This invention relates to improvements in a spout for inserting packages in receptacles.

In the patent to the American Machine & Foundry Company, as the assignee of E. D. Smith, No. 1114053, patented October 20, 1914, for cigarette packing machine, there is disclosed a spout adapted to enter a pouch and through which a package of cigarettes may be pushed to enter said pouch.

20 The present invention is an improvement upon the spout illustrated in the above patent and is adaptable for use upon the machine shown in said patent.

The invention consists in certain combinations which will be hereinafter described and then specifically set forth in the claims hereunto appended.

25 In the accompanying drawings, which form a part of this specification and in which like characters of reference indicate the same or like parts, Figure 1 is a front elevation partly broken away of a device constructed in accordance with the invention; and Fig. 2 is a cross-sectional view 30 taken on the line 2—2 in Fig. 1.

In the device selected to illustrate the invention, there is provided a frame consisting of a main section 1 and a removable section 2, said removable section being secured 40 to the main section by means of screws 3. The two sections, when assembled, form a frame having a rectangular aperture therein. There is further provided a pair of guide rods 4 mounted in suitable apertures 45 drilled in the sections 1 and 2 before referred to. These guide rods are thus supported by the frame and cross said aperture, one near each side wall thereof. Midway between the top and bottom walls of said 50 aperture are located a pair of stop studs 5 screwed into suitable threaded apertures in the side walls of the frame. Slidably mounted upon the guide rods 4 are a pair of blocks 6, one on either side of the stop studs 5 which act to limit the approaching

movement of the blocks 6. Secured to the blocks 6 are a pair of parallel rigid longitudinally flanged members 7 and these members are movable with the blocks and are adapted to enter a receptacle. The 60 members 7 are rigidly held to the blocks 6 by means of keepers 8 and screws 9, said screws passing through apertures in the keepers and in the members 7 and threading into the blocks 6. Each of the blocks 6 65 is provided with two counter-sunk apertures 10 concentric with the guide rods 4, and in each of these apertures 10 and bearing against the blocks 6 and against the frame, is a spring 11 coiled around the guide rod. 70 The springs 11 normally hold the blocks 6 in contact with the stop studs 5; but when a package is pushed between the blocks 6 and members 7 to enter a receptacle supported upon the exterior of said members, 75 the blocks and members yield against the action of the springs 11 so that the members will be moved apart to grip and hold the receptacle during the insertion of the package. After the package has been inserted in the 80 receptacle, a further movement thereof pushes the receptacle off from the spout members 7; and when both receptacle and inserted package are cleared from the members 7, the springs 11 again move the blocks 85 6 into contact with the stop studs 5, which action of course results in bringing the spout members 7 nearer together so that another receptacle may be easily slipped on the same. 90

Changes and variations may be made in the structure by means of which the invention is carried into effect. The invention, therefore, is not to be limited to the precise details of the structure shown and described. 95

What is claimed is:

1. In a spout for inserting packages in receptacles, the combination with a frame having a rectangular aperture formed therein, of a pair of guide rods supported by 100 said frame and crossing said aperture, a pair of stop studs supported by said frame and projecting into said aperture at points midway between opposite walls of said aperture, a pair of blocks slidably mounted on said guide rods one on either side of said stop studs, a pair of parallel rigid longitudinally flanged members supported by and movable with said blocks and adapted to enter a receptacle and between which a pack- 110

- age may be pushed into said receptacle, a pair of keepers for rigidly holding said members to said blocks, and springs coiled around said guide rods and bearing against 5 said frame and said blocks to normally hold said blocks in contact with said stop studs.
2. In a spout for inserting packages in receptacles, the combination with a frame having an aperture formed therein, of a 10 pair of guide rods supported by said frame and crossing said aperture, a pair of blocks slidably mounted on said guide rods, a pair of parallel rigid longitudinally flanged members supported by and movable with 15 said blocks and adapted to enter a recep-

tacle and between which a package may be pushed into said receptacle, means for rigidly holding said members to said blocks, springs coiled around said guide rods and bearing against said frame and said blocks 20 to normally cause an approaching movement of said blocks and said members, and means for limiting said approaching movement.

In testimony whereof, I have signed my name to this specification in the presence of 25 two subscribing witnesses.

RUDOLPH REJSEK.

Witnesses:

SYDNEY I. PRESCOTT,
ELIZABETH LOUISE RUSSELL.
